UNITED STATES PATENT OFFICE

EMMA GROTELUESCHEN, OF LEIGH, NEBRASKA

RUG AND MATTRESS CLEANING RACK

Application filed March 21, 1928. Serial No. 263,507.

The present invention relates to a beater rack for rugs and the like to constitute a firm elastic support, upon which they may be laid to apply frails or beaters to drive out the dust. In carrying out the invention, I provide a plurality of hinged sections so connected that the form may be compactly folded together for storage purposes. Ordinarily, rugs, mattresses and the like are cleaned of dust by laying them on the ground or in the cellar, which makes the operation of beating them—to free them of their contained dust—a very laborious operation. I, therefore, provide a plurality of foldable frames, which when extended form a long wide angular rectangular skeleton support for a large number of helical steel springs, providing an elastic surface, on which the beating operation may be performed. A plurality of pairs of rows of the springs are closely related and mounted on longitudinal rectangular frames, the several spring bottoms being securely anchored therein, the upper ends of the springs being anchored in a top rectangular frame on each section, to which the several springs are secured at the top, the several springs of each row being wired together so as to prevent side shifting, thus forming a stable elastic support, upon which the rugs or mattresses may be placed for beating. The several rack sections are connected by a right angled hinge having an eye for a pivotal point at the one side. The spring supports are mounted on the side opposite the pivot, thus permitting the several sections to be folded into compact relation. The invention therefore comprises a foldable rack consisting of a plurality of hinged sections of rectangular shape, each containing a large number of helical springs, supporting a beating surface and adapted, when out of use, to be folded compactly for storage. It embodies other more specific features of novelty, which will be hereinafter described and will be definitely indicated in the appended claim.

In the accompanying drawings illustrating the invention:

Figure 1 is a top plan of a folding rack embodying my invention.

Figure 2 is an end elevation of the rack when open.

Figure 3 is a side elevation.

Figure 4 is a bottom plane of the rack opened and

Figure 5 is a side elevation of the rack when folded for storage.

Referring now in detail to the drawings:—
 1—1 α , 1 β represents a plurality of rectangular frames, three in this instance, each section being formed by two parallel strips of sheet metal or other suitable material, indicated at 2—and rigidly connected at their ends by cross bars 2 α . The outside sections 1—1 β are approximately half the width of the middle section 1 α to permit the entire width when folded to fall within the limits of the middle section 1 α , as indicated in Figure 5. I mount a plurality of tapered helical springs closely related to form a good surface for rugs or mattresses to be cleaned with the lower ends of these springs anchored in the frame work formed by the strips 2 and the upper ends of the several springs are anchored directly in the rectangular tubular iron frames 5, constituting a strong framework on which the springs may be secured. In the two outer sections 1 and 1 β , the springs ends may be coiled around a side of the frame 5, and a plurality of transverse wires 5 α and lengthwise wires 7 prevent the springs from shifting laterally. In practice I employ eight rows of fifteen coils to a row, consisting of 120 coils in all. For convenience of illustration less than this number has been shown. It will be understood however that the number might be varied without departing from the scope of my invention. In the middle section 1 α , I employ 4 rows, the two outer rows of which may be similarly anchored to that described in connection with the section 1 α , the upper ends of the inner rows of the section 1 α being prevented from shifting by the interlinking of the wires 5 α and 7. The bottom frame work is provided with riveted angle bars 3 α , having dependent hinged barrels cooperating to receive pins to provide hinges 10, which permits the outside sections to be folded together and similar angle bars are riveted or otherwise secured to the outside

of the outer section, in which are pivotally mounted legs 11, to form a support for the rack. Similar pivoted legs 12 may be mounted at the ends of the middle sections 1a. The 5 corner legs 11 each carry a pivoted brace 13, slotted at its outer end and adapted to lock over a pin or bolt 14, on the inner side of the rack. A pair of pivoted legs 15 may be mounted midway of the length of the rack 10 to afford a firm support for the rack. Angle bars are secured to the outer edges of the outer sections and have pivotally secured to the outer sides thereof the legs 15, as shown in Figures 2 and 3.

15 Each of the angle bars 3a include a horizontal and a vertical flange, the latter depending from the outer side of the former. The angle bars 3a forming the inner side of each outer lower frame and the sides of the inner lower frame have the vertical flanges thereof of greater height than the width of the horizontal flanges, and also of greater height than the vertical flanges of the angle bars forming the outer sides of the outer upper frames. 20 The angle bars which have the vertical flanges of greater height are hinged together and the means providing the hinges are spaced from each other and spaced from the ends of such flanges. 25 The said vertical flanges of greater height, when the frames are folded constitute supports for and for maintaining the ends of the pairs of outer frames in superposed spaced relation with respect to the ends of the 30 pair of inner frames.

35 Having thus described my invention what I claim is new and desire to secure by Letters Patent is:

40 A cleaning rack comprising a lower inner and pair of lower outer sidewise opposed rectangular frames foldable relative to each other, the inner side of each outer frame and each side of the inner frame being in the form 45 of an angle bar having a horizontal flange and a vertical flange, the vertical flange depending from the outer side and of a height greater than the width of the horizontal flange, each of said frames including fixed, spaced lengthwise extending parallel flat narrow strips of a length corresponding to the length of said frames, supporting legs hinged 50 at their upper ends and foldable against and lengthwise of said frames, an upper inner and a pair of upper outer rectangular frames positioned 55 permanently in superposed spaced relation respectively over said lower inner and lower outer frames, said upper frames being independent of each other, a row of spaced upstanding coiled springs positioned on and 60 having the bottoms thereof secured to each strip, said springs extending into said upper frames, transversely and longitudinally extending retaining means anchored to the sides and ends of each upper frame and to the tops 65 of said springs whereby each lower frame

will bodily carry therewith that upper frame arranged thereover, and said vertical flanges being provided with spaced means spaced from the ends thereof for hinging the frames together, the said vertical flanges when the 70 frames are folded constituting supports for and for maintaining the ends of the pairs of outer frames in superposed spaced relation with respect to the ends of the pair of inner frames.

75 In testimony whereof I affix my signature.
EMMA. GROTELUESCHEN.
